C. F. STODDARD

AUTOMATIC MUSICAL INSTRUMENT

Filed April 21, 1924

Inventor

Charles F. Stoddard.

By his Attorney's
Clegg, Booth, Janney & Vannay.

UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

AUTOMATIC MUSICAL INSTRUMENT.

Application filed April 21, 1924. Serial No. 707,798.

This invention relates to automatic musical instruments such for instance as pianos; and it pertains more particularly to expression devices for such instruments, or to means 5 for governing playing intensities.

Among other objects, the invention is intended to provide apparatus capable of reproducing with great fidelity the manual performances of pianists and to reenact interpretations of musical compositions as rendered by well known artists of ability.

It is an object of this invention not only to reproduce accurately the various gradations of dynamic force with which the notes of a 15 musical composition are sounded, but also to reflect the mood and spirit of the manual performer, and thereby to give life and contrast to the mechanical rendition which shall make it approximate manual rendition even 20 more closely than has been possible before.

Other objects and advantages of the invention will appear hereinafter.

For illustration, the accompanying drawings show one practical embodiment of the 25 invention employing suitable pneumatically governed devices in cooperation with a piano action; but, as will appear to those skilled in the art, the invention is susceptible of embodiment in various constructions and organizations 30 other than that particularly shown and described herein. It will appear likewise that it is not indispensable that all the features of the invention be used conjointly since their respective substantial advantages 35 may accrue from their separate application in any practicable manner to a suitable playing instrument.

The figure is a semi-diagrammatic view of an apparatus embodying the invention.

Referring to the drawings, a player action chest 3 is provided comprising the usual player pneumatics, valves and ducts, not illustrated, for controlling the same. A wind trunk 7 connects the exhaust chest 3 with the wind chest 12 which may be referred to as the 45 regulated wind chest. A wind chest 14, which may be known as the high exhaust chest, is arranged for communication with the chest 12, and may also be connected by a wind trunk 5 with a source of pneumatic exhaust 6 of any usual or desired construction.

It is to be understood in the following description that where the term "pressure" is

used, pressures in their absolute sense is referred to—that is, relative to zero pressure or absolute vacuum as a base. However, due to the fact that sub-atmospheric pressures are commonly measured on a water gauge, which assumes atmospheric pressure as a base value, 55 the term "exhaust" will be used at times to avoid confusion, in its normal sense of vacuum of sub-atmospheric pressure. Thus, high exhaust is high vacuum, or low pressure; and as exhaust increases pressure decreases 60 and conversely.

In the illustrative apparatus of the drawings, the striker pneumatics of the wind chest 3 may be operated by the exhaust in the regulated exhaust chest 12. In order to vary the 70 blow struck by the striker pneumatics to thereby vary playing intensities, this regulated exhaust may be varied by subjecting it more or less to the influence of high exhaust in chest 14. For this purpose there has been 75 provided between the high exhaust chest 14 and the regulated exhaust chest 12 a passage 8 controlled by the throttle valve 9.

For purposes of simplicity of description, a single regulated exhaust chest has been 80 illustrated which controls pressures throughout the action chest of the piano. As will be understood by those skilled in the art, however, the action chest of automatic musical instruments is frequently divided into bass 85 and treble sections, in which case a separate regulated exhaust chest and controlling valves and pneumatics may be provided for each section in the usual manner.

The valve 9 may be operated by a variety 90 of different means. In this specific apparatus there has been selected for purposes of illustration the apparatus disclosed in the accompanying drawings now to be described. The valve 9 may be conveniently mounted on a stem passing through the upper wall of the exhaust chest 14 previously described. The valve stem is pivotally connected at 10 to the bar 11 which may be connected at one of its ends to a so-called accordion bellows 15 consisting of a plurality of separate bellows *a*, *b*, *c* and *d* secured together in a stack, one on top of another, the top board of the stack being secured to a fixed support A. Each of the bellows has a different extent of collapse, 100 as for instance the bellows *d* may have the greatest extent of collapse and the bellows *c*, *b*, and *a* may have progressively decreasing

extents of collapse. Each of the separate bellows of the accordion bellows is separately connected to valve boxes 17 by which the sections of the accordion bellows are controlled. 5 The said valve boxes may be of any of the conventional types commonly employed in the art and may be of the primary type illustrated at page 19 of "The Player Piano Up-to-Date" by William Braid White, published 10 1914 by Edward Lyman Bill, or may be of the primary or secondary type illustrated at page 49 of the same volume, or may be of the lock valve type illustrated in Stoddard Patent No. 1,409,479 of March 14, 1922, or may be of any 15 similar type depending upon the particular conditions to be met. The valve boxes are connected by suitable tubing 16 to tracker ducts 2^a, 2^b, 2^c and 2^d in the tracker bar 2. A spring 18 is also connected to the bar 11 to 20 maintain the accordion bellows normally in expanded position. The spring is not of sufficient strength, however, to effect opening movement of the accordion bellows when the sections thereof are subjected to exhaust. 25 The opposite end of the bar 11 is pivotally connected to a link 19 which is pivotally connected to an extension of the movable leaf 20 of the pneumatic 21. Pneumatic 21 is connected to the regulated exhaust chest 12 by 30 a wind trunk 22. The movable leaf 20 has attached thereto a regulator spring 23 which constantly urges it in an upward direction with a force depending on the extent to which the spring is stretched. As will be understood, as the pneumatic 21 is collapsed and 35 the spring is stretched, the force urging the pneumatic to open is increased and vice versa.

Assuming for the moment that the accordion bellows 15 remains fixed in open position 10 under the influence of the spring 18, the function of the pneumatic 21 and spring 23 in controlling the valve 9 may now be considered. Primarily this structure serves to maintain a substantially even tension in the 15 regulated exhaust chest 12 regardless of the number of notes being sounded at any given time by the player action. For instance, if a piano is in operation and the valve 9 is being maintained in substantial equilibrium 20 under the opposed forces acting on it, if a large number of player pneumatics are suddenly operated simultaneously, a large inrush of atmospheric air to the regulated exhaust chest 12 will result. This inrush of air will tend to reduce the exhaust of the 25 regulated exhaust chest and the pneumatic 21 will, therefore, tend to expand under the influence of its spring, thus permitting the valve 9 to move further away from its seat. 30 An additional quantity of air may, therefore, be drawn from the regulated exhaust chest 12 by the pump. This withdraw in turn would tend to increase the exhaust in the regulated exhaust chest and the pneumatic 21 would tend to collapse, thus again

restoring the valve 9 to equilibrium. A reverse condition would, of course, result in a reverse action, as for instance, if less than the usual number of pneumatics are operated at any given time, the tension in the regulated exhaust chest would tend to increase and the pneumatic 21 would tend to collapse thereby drawing the valve 9 closer to its seat and permitting less air to be withdrawn from the regulated exhaust chest by the pump. 75 This in turn would tend to decrease the tension in the regulated exhaust chest and the pneumatic 21 would tend to expand, thus again restoring the valve 9 to equilibrium. 75

In the apparatus illustrated, however, another factor affecting the valve 9 must be considered. As will be observed, the valve 9 is what may be termed an unbalanced valve, that is, the valve area itself is subjected to high exhaust, tending to pull the valve away from its seat and to regulated exhaust tending to pull the valve toward its seat. Since high exhaust is always greater than regulated exhaust, the resultant is an upward pull on the valve. If it be assumed that high exhaust be maintained substantially constant, it will be observed that this differential between regulated and high exhaust pulling upwardly on the valve assists in the regulation performed by the pneumatic 21, since, if the differential increases, an increased upward pull results tending to decrease the differential, while if the differential decreases, the upward pull decreases, which in turn tends to increase the differential. 90

Thus far it has been assumed that the accordion bellows remains in fixed position. As will be observed by those skilled in the art, however, this accordion bellows may be moved and controlled by applying exhaust, 105 preferably high exhaust, to the interior of the sections of the bellows in the manner set forth and described in patent to J. H. Dickinson, No. 1,444,632, patented February 13, 1923. 110

As in the above mentioned patent, if the accordion bellows or any of the sections thereof are collapsed, an opening movement of the valve 9 results and additional air is withdrawn from the regulated exhaust chest, 115 thereby tending to increase the tension therein. This results, however, in a partial collapse of the pneumatic 21 against the tension of its spring 23, the final result being an increase in the tension of the spring 23 and an increase in the exhaust governed thereby in pneumatic 21 and the regulated exhaust chest 12. As will be apparent, however, the pneumatic 21 will operate to maintain the new degree of exhaust substantially constant as before whatever the number of notes being sounded simultaneously. 120

To sum up, the apparatus thus far described produces automatically incremental changes in playing intensities, and it per-

forms a regulating function—that is, it maintains any given playing intensity whether one or many notes be sounded.

In the present description it has been assumed thus far that the degree of exhaust produced by the main source of power remains substantially constant. In the aforementioned patent, indeed, it was immaterial whether the exhaust produced by the main source of power remained constant or not in so far as the valve 9 was concerned, since changes in the degree of exhaust have no effect upon the valve 9 in the patent since this valve was of the knife valve or balanced valve type. In the present apparatus, however, the pressure produced by the source of power and maintained in the high exhaust chest 14 is of material importance, because, as explained before, the degree of exhaust maintained in the high exhaust chest 14 is one of the factors affecting the valve 9 to thereby govern playing intensities. This feature has been taken advantage of to increase the capacity of the present apparatus to produce variations in playing intensities beyond that of the apparatus of the patent, and to thereby render it more effective in reproducing with fidelity and accuracy the performances of artists of ability.

For this purpose it is proposed to deliberately vary the pressure maintained in the high exhaust chest by the source of power when desired and also to maintain it at a substantially constant level when so desired. However, before proceeding to a consideration of the specific means employed to accomplish this purpose, it may be convenient to consider the effect that variations in high exhaust will have on playing intensities.

As has previously been explained, the differential between regulated exhaust and high exhaust results in an upward pull on the valve 9. If, therefore, this differential is increased by increasing the degree of high exhaust, the upward pull on the valve is increased, and, therefore, in order that the valve may be maintained in equilibrium, one of the forces pulling downwardly on the valve must be increased. This results because the increased upward pull on the valve tends to pull the valve away from its seat to permit an increased amount of air to be withdrawn from the regulated exhaust chest which in turn tends to increase the degree of regulated exhaust which results in a tendency to collapse the pneumatic 21 thereby increasing the tension on the regulated spring 23. It is this increased tension within the pneumatic 21 acting downwardly on the valve which balances the increased upward pull on the valve to hold the valve in equilibrium, the result being that when the degree of high exhaust is increased, the degree of regulated exhaust is also increased. As will be apparent, by reverse operation, if the degree of high

exhaust is decreased, the degree of regulated exhaust will be correspondingly decreased. And these changes in the pressure of regulated exhaust, it will be observed, occur whatever the condition of the accordion bellows 15 may be. That is, whatever the pressure of regulated exhaust may be as determined by the condition of the accordion bellows, a change in the degree of high exhaust will cause a change in the degree of regulated exhaust.

In the present embodiment means have been provided to vary the degree of pressure in high exhaust chest 14, although, as will be apparent, the same result might be attained by controlling the exhaust produced by the source of power. Mounted on the upper board of the high exhaust chest 14 is a regulator bellows 201 which is in free communication with the high exhaust chest 14 through the passages 203. The reservoir bellows comprises a fixed leaf 204 and a movable leaf 205, the bellows being urged toward open position by means of a leaf spring 206.

A valve 213 is mounted on a valve stem 214 and is normally held in position against the valve seat 215 by means of a coil spring 216. As will be observed, free passage of atmospheric air is permitted to the high exhaust chest 14 when the valve 213 is open.

When the pump is operated to withdraw air from the high exhaust chest to reduce the pressure and create a partial vacuum in a well-known manner, if no movement of the valve 213 takes place, the pump will produce the highest exhaust within its capacity. It will be apparent, however, that movement of the valve 213 away from its seat will permit the flow of atmospheric air into the high exhaust chest to thereby reduce the degree of high exhaust. It will also be observed that exhaust in the high exhaust chest 14 will tend to collapse the regulator pneumatic 201 against the force of its spring 206, the greater the exhaust in the exhaust chest 14, the greater being the collapse of the pneumatic 201.

Neglecting for the moment the specific form of connection between the regulator bellows 201 and the valve stem 214, and assuming that some direct connection is present, it will be apparent that closing movement of the pneumatic 201 will move the valve 213 away from its seat to admit atmospheric air to the high exhaust chest 14.

The effect of this action will be to maintain the pressure in the high exhaust chest 14 at a substantially constant level. If the degree of exhaust tends to increase, the regulator pneumatic 201 will tend to collapse and due to this connection with the valve stem 214, the valve 213 will admit atmospheric air to the high exhaust chest 14 to thereby tend to decrease the degree of exhaust. Conversely, if the exhaust in the high exhaust chest 14 tends to decrease the regulator pneu-

matic 201 will tend to expand to draw the valve 213 more closely to its seat to admit less atmospheric air to the exhaust chamber 202, and the degree of exhaust therein will therefore tend to be increased.

It will be understood, therefore, that in the case of the valve 213, an equilibrium is set up and maintained between the force tending to open the valve and the forces tending to close the valve which maintain it in a substantially balanced condition.

Means are provided for connecting the movable leaf 205 of the regulator pneumatic with the valve stem 214, such means comprising preferably means for varying the operative relationship therebetween in order to secure varying effects.

Pneumatics 230 and 231 are mounted on the movable leaf 205 of the regulator pneumatic 201, and the pneumatic 231 is provided with an abutment 232 which projects outwardly into position for engagement with the valve stem 214. The valve stem 214 may conveniently be pivoted as at 234. A limit stop 236 is provided for the pneumatic 230 which is fixed to the leaf 205 and extends over and engages the outer face of the leaf 237 by means of an adjustable screw 238. A limit stop 239 is also provided for the pneumatic 231 which is fixed to the leaf 240 and extends over and engages the leaf 237 by means of an adjustable screw 241. The extent of movement of each of the pneumatics 230 and 231 may be adjusted by the set screws 238 and 241.

When the pneumatics 230 and 231 are in expanded condition, the limit stops 236 and 239 cause the leaf 240 to move with the leaf 205 of the regulator bellows 201 and transmit motion of the leaf 205 to the valve stem 214 through its pivotal connection therewith. When both of the pneumatics 230 and 231 are in expanded condition, this movement will not be transmitted until the regulator pneumatic 201 is nearly collapsed. On the other hand, when the bellows 230 and 231 are both collapsed, a very slight movement of the regulator bellows may cause movement of the valve stem and valve. By providing bellows 230 and 231 with different opening movements, two different intermediate positions of the leaf 205 may be secured in which movement thereof will be transmitted to the valve 213.

In each of these positions of the regulator bellows 201 a different condition of equilibrium will be set up due to the fact that in each position the spring 206 exerts a different opening force upon the leaf 205. In its wide open position the spring exerts its least degree of pressure, while in its closed position the spring, being held to a greater degree of compression, exerts a greater force.

The result of such operations on the pressure in the high exhaust chest 14 will now be apparent. When the pneumatics 230 and 231

are caused to collapse, the degree of exhaust in the high exhaust chest 14 will be at a minimum, and conversely when the pneumatics 230 and 231 are caused to expand, the degree of exhaust in the high exhaust chest 14 will be at its highest level. When one of the pneumatics is collapsed and the other is expanded, intermediate pressures are secured in the high exhaust chest 14. In any one of the positions indicated the regulator bellows 201 of course will control the valve 213 to maintain the pressure established at a substantially constant level, and it will continue to do so until a change in the positions of the pneumatics 230 and 231 causes a new condition of equilibrium to be set up.

Means are provided for controlling the operation of the bellows 230 and 231 automatically from the tracker bar. For this purpose, a valve block 250 is provided in which are mounted an outside valve 251 and an inside valve 252 which may be operated by diaphragms 253 and 254 respectively. An exhaust chamber 255 is provided which is constantly maintained under exhaust by means of the passage 256 connected to the high exhaust chest 14. When the valves are in their normal seated position, the passage 257 to the pneumatic 230 is open to atmospheric air through the port 258 and the pneumatic 230 remains therefore in expanded condition. On the other hand, the passage 259 is subjected to exhaust from the exhaust chamber 255 and the pneumatic 231, therefore, is normally maintained in collapsed position.

The normal position, therefore, of the pneumatics will be as illustrated, and the normal degree of exhaust in the high exhaust chest 14 will be at the first step above its minimum. If, under these conditions, atmospheric air is admitted to the diaphragm chamber 261 through the passage 262, the valve 252 will be raised cutting off the passage of atmospheric air through the port 258 and allowing suction through the passage 263 to collapse the pneumatic 230. Under these conditions the pneumatics 230 and 231 will both be collapsed and the degree of exhaust in the high exhaust chest 14 will be at a minimum.

If, under these conditions, atmospheric air is admitted to the diaphragm chamber 265 through the passage 266, valve 251 will be raised, exhaust from the chamber 255 will be cut off, and atmospheric air will be allowed to enter the pneumatic 231 through the port 267 to thereby expand the pneumatic and increase the degree of exhaust in the high exhaust chest 14. By manipulation of the valves 251 and 252 through the admission of atmospheric air to the passages 262 and 266, the pneumatics 230 and 231 may be controlled at will to cause them to assume varying positions to thereby establish and maintain varying degrees of exhaust in the high exhaust chest 14.

Passages 262 and 266 may be connected to the tracker vents 276 and 276^a in order that the valves 251 and 252 may be controlled automatically by a suitable note sheet.

The operation of the apparatus will be apparent from the foregoing description. To sum up, however, valves 251 and 252 are controlled by openings in the note sheet to operate the pneumatics 230 and 231 to cause varying pressures to be established in the high exhaust chest 14. Such pressures, when established, are maintained at a substantially uniform level by the regulating action of the regulator bellows 201. In normal operation, that is with tracker vents 276 and 276^a both closed, the degree of exhaust may be conveniently maintained at an intermediate level in order that pressures both below and above this level may be established by proper openings in the note sheet. Such changes in pressure being established in the high exhaust chest 14 also affect changes in playing intensities as before described. The accordion bellows 15 and its component parts *a*, *b*, *c* and *d*, controlled by their respective valve mechanisms 17, however, maintain their respective capacities to produce step changes whatever the pressure established in the high exhaust chest may be. The step changes established, however, will vary depending upon the particular pressure established in the high exhaust chest.

The apparatus illustrated and described herein is similar in certain respects to that illustrated and described in a copending application filed by Charles F. Stoddard, March 12, 1924, Serial No. 698,599. In that application such invention as is common to the two applications is claimed generically. Herein, among other things, there is illustrated and described the adaptation of certain features of the aforementioned application to a different apparatus and no claim is broadly made herein to the common subject matter.

Nevertheless, the present invention may be variously modified and embodied within the scope of the subjoined claims.

I claim as my invention:

1. In an automatic musical instrument having player pneumatics and a source of pneumatic power, in combination, a throttle valve interposed between said player pneumatics and source of pneumatic power, and influenced by the force of exhaust from said source of pneumatic power toward open position; an accordion bellows connected to said throttle valve comprising sections having different extents of movement; means to collapse said sections selectively to thereby vary the degree of exhaust applied to said player pneumatics; and additional pneumatic means connected to said throttle valve to maintain at said player pneumatics the degree of exhaust established by said varying means whether one or many notes be sounded simultaneously.

2. In an automatic musical instrument having player pneumatics and a source of pneumatic power, in combination, a throttle valve interposed between said player pneumatics and source of pneumatic power, and influenced by the force of exhaust from said source of pneumatic power toward open position; an accordion bellows connected to said throttle valve comprising sections having different extents of movement; means to collapse said sections selectively to thereby vary the degree of exhaust applied to said player pneumatics; additional pneumatic means connected to said throttle valve to maintain at said player pneumatics the degree of exhaust established by said varying means whether one or many notes be sounded simultaneously; and means for altering the force of exhaust from said source of pneumatic power acting on said throttle valve to thereby alter the degrees of exhaust established and maintained by the aforesaid means.

3. In an automatic musical instrument having player pneumatics and a source of pneumatic power, in combination, a throttle valve interposed between said player pneumatics and source of pneumatic power, and influenced by the force of exhaust from said source of pneumatic power toward open position; an accordion bellows connected to said throttle valve comprising sections having different extents of movement; means to collapse said sections selectively to thereby vary the degree of exhaust applied to said player pneumatics; additional pneumatic means connected to said throttle valve to maintain at said player pneumatics the degree of exhaust established by said varying means whether one or many notes be sounded simultaneously; means for altering the force of exhaust from said source of pneumatic power acting on said throttle valve to thereby alter the degrees of exhaust established and maintained by the aforesaid means; and means to maintain the force of exhaust substantially constant at whatever level it is set by said altering means.

4. In an automatic musical instrument having player pneumatics and a source of pneumatic power, in combination, a throttle valve interposed between said player pneumatics and source of pneumatic power, and influenced by the force of exhaust from said source of pneumatic power toward open position; a rigid element pivotally connected to said valve; an accordion bellows connected to said rigid element, comprising sections having different extents of movement; means to collapse said sections selectively to thereby vary the degrees of exhaust applied to said player pneumatics; and additional pneumatic means pivotally connected to said rigid element to maintain at said player pneumatics the degree of exhaust established by said varying means whether one or many notes are sounded simultaneously.

5. In an automatic musical instrument having player pneumatics and a source of pneumatic power, in combination, a throttle valve interposed between said player pneumatics and source of pneumatic power, and influenced by the force of exhaust from said source of pneumatic power toward open position; a rigid element pivotally connected to said valve; an accordion bellows connected to said rigid element, comprising sections having different extents of movement; means to collapse said sections selectively to thereby vary the degree of exhaust applied to said player pneumatics; additional pneumatic means pivotally connected to said rigid element to maintain at said player pneumatics the degree of exhaust established by said varying means whether one or many notes are sounded simultaneously; and means for altering the force 10 of exhaust from said source of pneumatic power acting on said throttle valve to thereby alter the degrees of exhaust established and maintained by the aforesaid means.

6. In an automatic musical instrument having player pneumatics and a source of pneumatic power, in combination, a throttle valve interposed between said player pneumatics and source of pneumatic power, and influenced by the force of exhaust from said source of pneumatic power toward open position; a rigid element pivotally connected to said valve; an accordion bellows connected to said rigid element, comprising sections having different extents of movement; means to collapse said sections selectively to thereby vary the degree of exhaust applied to said player pneumatics; additional pneumatic means pivotally connected to said rigid element to maintain at said player pneumatics the degree of exhaust established by said varying means whether one or many notes are sounded simultaneously, including a pneumatic having a variable tension element tending to open it; and means for altering the force of exhaust from said source of pneumatic power acting on said throttle valve to thereby alter the degrees of exhaust established and maintained by the aforesaid means.

7. In an automatic musical instrument having player pneumatics and a source of pneumatic power, in combination, a throttle valve interposed between said player pneumatics and source of pneumatic power, and influenced by the force of exhaust from said source of pneumatic power toward open position; a rigid element pivotally connected to said valve; an accordion bellows connected to said rigid element, comprising sections having different extents of movement; means to collapse said sections selectively to thereby vary the degree of exhaust applied to said player pneumatics; and additional means pivotally connected to said rigid element to maintain at said player pneumatics the degree of exhaust established by said varying means whether one or many notes are sounded simultaneously, including a pneumatic having a variable tension element tending to open it; means for altering the force of exhaust from said source of pneumatic power acting on said throttle valve to thereby alter the degrees of exhaust established and maintained by the aforesaid means; and means to maintain the force of exhaust substantially constant at whatever level it is set by said altering means.

8. In an automatic musical instrument having player pneumatics and a source of pneumatic power, in combination, a throttle valve interposed between said player pneumatics and source of pneumatic power, and influenced by the force of exhaust from said source of pneumatic power toward open position; a rigid element pivotally connected to said valve; an accordion bellows connected to said rigid element, comprising sections having different extents of movement; means to collapse said sections selectively to thereby vary the degree of exhaust applied to said player pneumatics; additional means pivotally connected to said rigid element to maintain at said player pneumatics the degree of exhaust established by said varying means whether one or many notes are sounded simultaneously; and means for altering the force of exhaust from said source of pneumatic power acting on said throttle valve to thereby alter the degrees of exhaust established and maintained by the aforesaid means.

9. In an automatic musical instrument having player pneumatics and a source of pneumatic power, in combination, a throttle valve interposed between said player pneumatics and source of pneumatic power, and influenced by the force of exhaust from said source of pneumatic power toward open position; a rigid element pivotally connected to said valve; an accordion bellows connected to said rigid element, comprising sections having different extents of movement; means to collapse said sections selectively to thereby vary the degree of exhaust applied to said player pneumatics; additional means pivotally connected to said rigid element to maintain at said player pneumatics the degree of exhaust established by said varying means whether one or many notes are sounded simultaneously, including a pneumatic having a variable tension element tending to open it; and means for altering the force of exhaust from said source of pneumatic power acting on said throttle valve to thereby alter the degrees of exhaust established and maintained by the aforesaid means; and means to maintain the force of exhaust substantially constant at whatever level it is set by said altering means.

10. In testimony whereof, I have signed my name to this specification this 17th day of April, 1924.

CHARLES F. STODDARD.

In testimony whereof, I have signed my name to this specification this 17th day of April, 1924.

CHARLES F. STODDARD.
